DESIGN FOR AN INHALER

Allan C. Hoffman, Milldale, and Frederick Reutter, Waterbury, Conn., assignors to Scovill Manufacturing Company, Waterbury, Conn., a corporation of Connecticut

Application March 2, 1939, Serial No. 83,292

Term of patent 7 years

To all whom it may concern:

Be it known that we, Allan C. Hoffman, a citizen of the United States, residing at Milldale, county of Hartford, State of Connecticut, and Frederick Reutter, a citizen of the United States, residing at Waterbury, county of New Haven, State of Connecticut, have invented a new, original, and ornamental Design for Inhalers, of which the following is a specification, reference being had to the accompanying drawing, forming part thereof.

Fig. 1 is a side elevational view of an inhaler in closed position, embodying our new design,

Fig. 2 is a top plan view of the same,

Fig. 3 is a bottom plan view of the same, and

Fig. 4 is a perspective view of the inhaler in open position.

We claim:

The ornamental design for an inhaler, substantially as shown.

ALLAN C. HOFFMAN.
FREDERICK REUTTER.
